CLAIM

The ornamental design for a ceiling fan, as shown and described.

DESCRIPTION

FIG. 1 is a top perspective view of a ceiling fan, showing our new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

Portions of the ceiling fan are shown in broken lines, and portions of the ceiling fan shown in broken lines form no part of the claimed design. Portions of the ceiling fan blades shown in jagged break lines show an unclaimed indeterminate length for the ceiling fan blades. Portions of the ceiling fan blades shown in jagged break lines form no part of the claimed design.

1 Claim, 8 Drawing Sheets
